HARRY E. STILLIANS, OF EL PASO, TEXAS.

COMBINATION FILING-BLOCK AND SAWING-BOARD.

1,211,888.

Specification of Letters Patent.

Patented Jan. 9, 1917.

Application filed March 25, 1916. Serial No. 86,737.

To all whom it may concern:

Be it known that I, HARRY E. STILLIANS, a citizen of the United States, residing at El Paso, in the county of El Paso and State 5 of Texas, have invented certain new and useful Improvements in Combination Filing-Blocks and Sawing-Boards, of which the following is a specification.

My invention relates to a work holding 10 device and more particularly to a jeweler's combination wood filing block and sawing board.

The primary object of my invention resides in the provision of a novel supporting 15 means for receiving a sawing board as well as a wood filing block, novel fastening means being associated with the wood filing block for removably and adjustably holding the sawing board in various adjusted positions 20 in the support.

Another object of this invention resides in the provision of a novel clamping means associated with the supporting means for 25 removably holding the supporting means on a suitable support, such as the edge of a work-bench.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

40 In the drawings, Figure 1 represents a side elevational view of my invention, the dotted lines illustrating the sawing board in an extended position as well as illustrating the position and arrangement of the fastening means for adjustably holding the supporting board in position. Fig. 2 is a front end elevational view of my invention illustrating to advantage the arrangement of the sawing board in the supporting means 45 as well as the relation of the wood filing block to the sawing board. Fig. 3 is a longitudinal sectional view of the wood filing 50

block illustrating to advantage the construction and arrangement of the fastening means. Fig. 4 is a fragmentary top plan view of the sawing board.

Referring more particularly to the drawings in which similar reference numerals designate like corresponding parts throughout the various views, I provide an elongated 60 rectangular supporting plate 1 with a longitudinal sawing board receiving recess 2, the plate being further provided adjacent its forward end with standards 3 integral with the outer sides of the plate, shoulders 4 being provided at the junctures of the standards with the sides of the plate to serve a purpose to be hereinafter described.

Referring more particularly to the drawings in which similar reference numerals designate like corresponding parts throughout the various views, I provide an elongated 65 rectangular supporting plate 1 with a longitudinal sawing board receiving recess 2, the plate being further provided adjacent its forward end with standards 3 integral with the outer sides of the plate, shoulders 4 being provided at the junctures of the standards with the sides of the plate to serve a purpose to be hereinafter described.

Slidably disposed in the recess 2 and of a configuration somewhat similar to the configuration of the recess is my improved sawing board 5, said board being provided at its outer edge with a V-shaped notch 6 to facilitate the sawing of a piece of metal without scarring the board or interfering 75 with the sawing operation.

In order to adjustably and removably maintain the sawing board 5 in position in the recess I have provided my improved wood filing block 7 which is preferably of 80 a rectangular configuration having the forward end cut diagonally, as illustrated by the numeral 8. This block is placed between the sides of the standards and rests upon the shoulders 4, the bottom of the block being arranged in close relation with the upper surface of the sawing board, as illustrated to advantage in Fig. 2, while the forward diagonal cut end of the block projects a slight distance beyond the forward edge 90 of the plate. When in this position by the use of suitable fastening devices, preferably screws 9, which pass through the standards and engage the block, the latter is maintained in substantial rigid yet removable relation with the standard. Preparatory to securing the block in position a bolt including a head 10 and a shank 11 is associated with a transverse opening 12 in the block. The head 10 is countersunk in a recess 13 which communicates with the opening while a nut 14 is engaged upon the free threaded end of the shank and countersunk in a recess 15 communicating with the opposite end

of the opening and arranged in the bottom 5 of the block. In use, it will be apparent that after the block has been secured in position by engaging the slotted head 10 with a suitable tool, (not shown) and rotating the shank the free end of the shank will be forced into binding engagement with upper surface of the sawing board and will thereby maintain the sawing board in an adjustable and substantially rigid yet removable position with respect to the plate. For the purpose of removably maintaining the plate in position preferably on the edge of a work-bench I have formed integral with 15 the forward edge of the bottom of the plate, an angularly bent arm 16 the free end of which adjustably receives the clamping screw 17. This clamping screw includes a thumb piece 18 and an engaging disk or 20 head 19 which when the thumb piece is operated is forced into engagement with the under edge of the top of a work-bench, as shown in Fig. 1 of the drawings.

The operation of my invention is as follows: As was set forth this arrangement is particularly adapted for use by jewelers when sawing, filing or otherwise working on a piece of jewelry. Should it be desired to saw a piece out of a ring or the like, and 30 assuming that the sawing board is within the recess 2, by releasing the free end of the shank 11 of the bolt and by pressing the rear end of the board forwardly, the front end in which the notch is provided can be arranged 35 in its desired position. Now by tightening the bolt so that the free end of the shank will engage the upper surface of the board, the latter will be maintained in a substantially rigid yet removable position with respect to the plate. The wood filing block 7 serves particularly as a means for receiving 40 a piece of jewelry when the jeweler desires to file a piece of jewelry. It will of course be understood that the clamping screw allows the device to be clamped to various 45 supports.

Although I have shown and described the preferred embodiment of my invention I desire it to be understood that I am not to be limited to the exact details shown; however, I desire that great stress be laid upon the arrangement of the supporting plate for receiving the sawing board and the wood filing block as well as the fastening means associated with the block for adjustably maintaining the sawing board in various positions on the plate.

From the above description taken in connection with the accompanying drawings, it 60 can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my invention and that various minor changes in detail of construction, proportion and arrangement of the parts may be made within the scope of the appended claims and without sacrificing any of the advantages of my invention.

I claim:

1. In a device of the character described a supporting plate having a longitudinal recess therein, a sawing board slidably mounted in the recess, a filing block resting on the upper surface of the plate and rigid therewith and also arranged in close relation with the upper surface of the sawing board, and fastening means mounted in and passing through the filing block to frictionally engage the sawing board whereby to maintain the sawing board in various adjusted positions on the plate.

2. In a device of the character described, an elongated and relatively flat supporting plate, means for removably clamping the plate in position, a sawing board slidably mounted on the upper face of the plate, filing means rigidly connected to the plate and arranged above the sawing board, and fastening means mounted in the filing means for adjustably and removably maintaining the sawing board in various adjusted positions on the plate.

3. In a device of the character described, an elongated and relatively flat supporting plate having a longitudinal recess in the upper surface thereof, a sawing board slidably mounted in the recess, a wood filing block rigidly mounted on the upper face of the plate and in close relation with the sawing board, and fastening means extending through the filing block and adjustable into frictional engagement with the upper surface of the sawing board for maintaining the sawing board in various adjustable positions with respect to the plate.

4. In a device of the character described, a supporting plate having a longitudinal recess in the upper surface thereof, a sawing board slidably mounted in the recess, standards formed integral with the sides of the plate adjacent the forward end thereof, a filing block disposed on the upper surface of the plate between the standards, means for removably securing the filing block between the standards, and fastening means associated with the block for adjustably and removably maintaining the sawing board in position in the recess.

5. In a device of the character described, including a plate, a sawing board slidably associated with the plate, a filing block associated with the plate and having an opening therethrough, a bolt countersunk in the block and arranged in the opening, and a

nut associated with the free end of the bolt and countersunk in the bottom of the block, the free end of the bolt engaging the upper surface of the board for removably and adjustably maintaining the board in position on the plate.

In testimony whereof I affix my signature in presence of two witnesses.

HARRY E. STILLIANS.
